INTERNAL COMBUSTION ENGINE CONTROL

Ede Kund, Budapest, Hungary

Application May 28, 1935, Serial No. 23,820
In Hungary June 7, 1934

9 Claims. (Cl. 192—.01)

As is well known, intake manifolds heated by exhaust gases are advantageous in that less fuel precipitates on the manifold when the throttle is opened suddenly and, therefore, the engine accelerates well even in case the air-fuel-mixture is relatively weak. On the other hand, intake manifolds heated by exhaust gases possess the well-known disadvantage that by opening the throttle fully, the heated intake manifold lowers the volumetric efficiency of the engine and thereby diminishes its output.

It would be desirable to get the manifold hot in the moment when the throttle opens and thereupon to have it cooled down gradually.

One object of my invention is to provide a device adapted to get the manifold hot during the time when the engine is driven by the vehicle and to get it cool when the engine is under charge, a further object of my invention being to provide a device by which during the time when the engine is driven by the vehicle the engine consumes no fuel at all or at least as little as possible.

According to the present invention, both above mentioned objects may be attained by introducing exhaust gases into the intake manifold during the time when the vehicle runs by its own forces of inertia or by the action of a sloping road, at which time the engine is driven by the vehicle. Thereby, on the one side, the vacuum in the intake will be eliminated or at least highly diminished and, in consequence thereof, aspiration of the air-fuel-mixture will cease completely or almost completely and, on the other side, the exhaust gases introduced, heat the manifold as desired. At the moment the throttle opens, introduction of the exhaust gases is cut off whereupon the aspiration of the air-fuel-mixture will become normal again. At this moment, however, the intake manifold is very hot owing to the exhaust gases having been introduced previously and, accordingly, no fuel will precipitate on the manifold. Thereby very good and efficient acceleration of the engine is obtained. The stream of air-fuel-mixture sucked in cools gradually the intake which is no longer heated by the exhaust gases and, accordingly, within a short time the volumetric efficiency gets as high as in the case of an intake which is unheated.

It will be seen from the foregoing that my invention unites the advantages of heated and unheated intakes, at the same time eliminating all their disadvantages and, aside from the foregoing, diminishes essentially the consumption of

fuel by checking the superfluous consumption during the time when the engine is driven by the vehicle. Thereby, simultaneously, the braking effect of the engine is also diminished because the said braking effect is less when sucking takes place without a vacuum than in the case when the said sucking takes place with a great vacuum and almost fully closed throttle.

The invention is illustrated by way of examples in the accompanying drawing, in which: Fig. 1 shows diagrammatically one embodiment of the device according to my invention adapted for engines, the intake manifold of which has no heating jacket, and Fig. 2 shows a modification adapted for engines, the intake manifold of which is provided with a heating jacket, like reference letters indicating like parts in both figures.

According to Fig. 1, the intake manifold *a* communicates with the exhaust pipe by means of a pipe *c*, a butterfly-valve *b* being provided to cut off the said communication under conditions to be set out later; *d* is the throttle of the carburetor to be controlled as usual by means of a foot-control lever *e* keyed to a shaft *f*. To the said shaft *f*, another lever *g* is also keyed which may move against the action of a spring *i* in the direction of the arrow *h* if and when the said control-lever *e* is pressed down. A further spring *j* is also provided to withhold the lower end of a rocker-arm *k* when the said foot-control lever *e* is pushed down. Accordingly, by pushing down the said foot lever *e* the upper end of the said rocker *k* will move first and will thereby close the said butterfly-valve *b* through a connecting rod *l* attached to a lever *m* integral with the axis of said valve *b*. When the butterfly-valve *b* is closed the further pressing down of the control lever *e* cannot result in a further movement of the upper end of the said rocker *k* and, therefore, the throttle *d* will open through the action of the lower arm of said rocker *k* which is now able to overcome the resistance of the said spring *j* and thereby actuates the throttle *d* by means of a rod *n* and a lever *o* integral with the axis of said throttle. When the foot control lever *e* is released, it is the throttle *d* which closes first, the said closing taking place under the action of the springs *i* and *j* and the valve *b* will open subsequently the said opening taking place under the action of the spring *i*. The reference letter *p* designates the usual clutch-pedal, and when the said clutch-pedal *p* is pushed down to declutch the engine the said pedal *p* will actuate not only the clutch control rod *q* as usual, but also the said butterfly-valve *b*. The clutch-pedal

is attached to a cable *r* connected to the butterfly-valve *b* by means of the above mentioned lever *m*, and thereby the valve *b* will be closed. The said closing is performed against the action of 5 the said spring *i*. The pedal *p* when released returns into its original position under the action of the spring of the clutch (not shown); thereby the cable *r* will get loose and thus allows the spring *i* to open the valve *b* by means of the 10 rocker *k*, connecting rod *l*, and the lever *m*.

According to Fig. 2, the connections of the control-pedal *e* with the throttle *d* and the valve *b* are quite the same as in the case of Fig. 1. The clutch-pedal *p*, however, instead of being attached 15 to the valve *b*, is connected with a change-over valve *u* controlling the heating jacket *v* of the intake *a*. The said connections being effected by means of a rod *s* and a lever *t* integral with the axis of said valve *u*, such that when the clutch-pedal *p* is pushed down, the change-over valve 20 *u* establishes communication between the pipe *c* and the heating jacket *v* of the intake *a*. Should at the moment when the clutch-pedal *p* is pushed down, the pedal *e* controlling the throttle *d* be in its extreme idle position so that the 25 valve *b* is open, then exhaust gases will get from pipe *c* into the heating jacket *v* of the intake *a*, and will heat the said intake *a*, the gases escaping from the heating jacket *v* through a conduit 30 pipe *w*. In case the clutch-pedal *p* is in its operative position, the change-over valve *u* cuts off communication between the heating jacket *v* and the pipe *c* leaving the communication between the pipe *c* and the intake *a* free. Accordingly, in that case operation of the device will be 35 quite the same as that of Fig. 1.

What I claim is:—

1. A device for controlling the operation of internal combustion engines for vehicles, comprising a communicative conduit between the intake and the exhaust, valve means positioned in said conduit, and means for actuating the said valve means to establish and cut off the said communication between the intake and the exhaust, 40 said valve means being operatively connected with the clutch-control-lever of the engine.

2. A device for controlling the operation of internal combustion engines for vehicles, comprising a communicative conduit between the intake 50 and the exhaust, valve means positioned in said conduit, and means for actuating the said valve means to establish and cut off the said communication between the intake and the exhaust, said valve means being operatively connected both 55 with the clutch-control-lever and with the means actuating the throttle of the engine, the said connection being adapted to automatically establish communication between the intake of the engine and the exhaust pipe when the clutch-lever is in its operative position and, simultaneously, the throttle control lever is in its extreme idle position, and for cutting off the said communication when the said clutch-lever is in its disengaged position or the throttle control lever is in one 60 of its loading positions, i. e. in a position other than the said extreme idle position.

3. A device for controlling the operation of internal combustion engines for vehicles, comprising a communicative conduit between the intake 70 and the exhaust, valve means positioned in said conduit, and means for actuating the said valve means to establish and cut off the said communication between the intake and the exhaust, said valve means being operatively connected with 75 the clutch-control-lever of the engine, which

lever, in its disengaged position, positively closes the said valve means, at least one spring being provided to open the said valve means when the said clutch-control-lever is in its operative position. 5

4. A device for controlling the operation of internal combustion engines for vehicles, comprising a communicative conduit between the intake and the exhaust, valve means positioned in said conduit, means for actuating the said valve means, said actuating means being adapted for establishing the said communication between the intake of the engine and the exhaust pipe when the clutch-lever is in its operative position and, simultaneously, the throttle control lever is in its extreme idle position, and for cutting off the said communication when the said clutch-lever is in its disengaged position or the throttle control lever is in one of its loading positions, i. e. in a position other than the said extreme idle position. 10

5. A device for controlling the operation of internal combustion engines for vehicles, comprising a communicative conduit between the intake and the exhaust, valve means positioned in said conduit, means for actuating the said valve means to establish and cut off the said communication between the intake and the exhaust, a heating jacket encircling the said intake, and valve means therefor adapted to establish and cut off communication between the said conduit and the heating jacket. 15

6. A device for controlling the operation of internal combustion engines for vehicles, comprising a communicative conduit between the intake and the exhaust, valve means positioned in said conduit, means for actuating the said valve means to establish and cut off the said communication between the intake and the exhaust, a heating jacket encircling the said intake, and valve means therefor adapted to establish and cut off communication between the said conduit and the heating jacket, said valve means for the said heating jacket being operatively connected with the actuating means to be controlled by the engine operator. 20

7. A device for controlling the operation of internal combustion engines for vehicles, comprising a communicative conduit between the intake and the exhaust, valve means positioned in said conduit, means for actuating the said valve means to establish and cut off the said communication between the intake and the exhaust, a heating jacket encircling the said intake, and valve means therefor adapted to establish and cut off communication between the said conduit and the heating jacket, said valve means for the said heating jacket being operatively connected with the clutch-control-lever, the said connection being such that the said valve means is held open when the said clutch-control-lever is in its disengaged position. 25

8. A device for controlling the operation of internal combustion engines for vehicles, comprising a communicative conduit between the intake and the exhaust, valve means positioned in said conduit, means for actuating the said valve means to establish and cut off the said communication between the intake and the exhaust, a heating jacket encircling said intake, additional valve means adapted to establish and cut off communication between the said conduit and said heating jacket, and means for actuating the additional valve means to introduce exhaust gases into the heating jacket during the time when the engine is idling. 30

9. A device for controlling the operation of internal combustion engines for vehicles, comprising a communicative conduit between the intake and the exhaust, valve means positioned in said conduit, means for actuating the said valve means to establish and cut off the said communication between the intake and the exhaust, a heating jacket encircling said intake, additional valve means adapted to establish and cut off communication between the said conduit and said heating jacket, and means for actuating the additional valve means to introduce exhaust gases into the heating jacket during the time when the engine is idling. 35

9. A device for controlling the operation of internal combustion engines for vehicles, comprising a communicative conduit between the intake and the exhaust, valve means positioned in said conduit, means for actuating the said valve means to establish and cut off the said communication between the intake and the exhaust, a heating jacket encircling said intake, additional valve means adapted to establish and cut off communication between the said conduit and said heating jacket, and means for actuating the additional valve means, the means for actuating both valves

being adapted to establish communication between the exhaust pipe of the engine and the intake when the throttle control lever is in its extreme idle position and, simultaneously, the clutch-lever is in its operative position, and for establishing communication between the exhaust pipe and the heating jacket of the intake when the throttle control lever is in its extreme idle position and, simultaneously, the clutch-lever is in its disengaged position.
